MANIFOLDING APPARATUS FOR WRITING MACHINES

John Q. Sherman, Dayton, Ohio; Katherine M. Sherman, William C. Sherman, and Wellmore B. Turner, executors of said John Q. Sherman, deceased

Application January 29, 1934, Serial No. 708,902

31 Claims. (Cl. 197—133)

This invention relates to paper feeding means for writing machines, and more particularly to alternately operable devices by which record material may be fed at will, either positively or frictionally about a platen roll and past writing position.

In modern commercial practice it is quite desirable to produce multiple copies of records by manifolding operation wherein it is essential that superposed printed forms be maintained in accurate registry and alignment at the writing position, for which the usual frictional feed means found on commercial typewriters is ineffective, and which necessitates the use of positive feeding mechanism for the superposed forms. It is likewise desirable when the writing machines are not being used for manifolding printed forms that the customary frictional feeding means shall be readily available for use with correspondence stationery and for other ordinary writing machine operations.

The object of the invention is to improve the construction as well as the means and mode of operation of writing machines whereby they will not only be more efficient in use, but will be capable of a wider range of usefulness, of greater convenience, simple construction, and unlikely to get out of repair.

A further object of the invention is to provide a writing machine with optionally usable frictional and positive feeding devices for record material.

A further object of the invention is to adapt an ordinary commercial typewriter for positively feeding superposed printed forms in accurate registry and alignment without interfering with the alternate use of the customary frictional feeding means with which such writing machines are regularly equipped, for feeding other forms of stationery.

A further object is to provide alternative writing material feeding devices and means for rendering either of such feeding devices inoperative at the will of the operator.

A further object is to provide alternatively operable feeding devices and selective means for rendering either of said devices operative and the other inoperative at will.

A further object of the invention is to provide alternating means for positively and frictionally feeding record material through indefinite periods of operation at the will of the operator.

A further object of the invention is to provide control means for alternating the operative condition of the positive and frictional feeding means by which the setting of one such feeding means in operative condition will automatically render the other such feeding means inoperative.

A further object of the invention is the utilization of conventional writing machine mechanism

in conjunction with positive feeding means for the record material.

5 A further object of the present invention is the incorporation of positive feeding means for record material in a conventional writing machine while preserving the normal and customary functions thereof.

10 A further object of the invention is the provision of positive feeding means for writing material applicable to a conventional writing machine without disturbing the customary platen roll and associated frictional feeding devices.

15 A further object of the invention is the incorporation of positive and frictional feeding means for writing material in a single writing machine.

20 With the above primary and other incidental objects in view, as will more fully appear in the specification, the invention consists of the features of construction, the parts and combinations thereof, and the mode of operation, or their equivalents, as hereinafter described and set forth in the claims.

25 Referring to the accompanying drawings, wherein is shown the preferred but obviously not necessarily the only forms of embodiment of the invention, Fig. 1 is a perspective view of a portion of the platen carriage of a writing machine including the platen roll and associated parts to 30 which has been applied means for positively feeding the record material. Fig. 2 is an end elevation thereof. Fig. 3 is an end elevation similar to Fig. 2 but illustrating an alternative form of paper guiding means for rendering the positive 35 feeding means ineffective. Fig. 4 is a detail view somewhat diagrammatic of an alternative paper guiding means for rendering the frictional feeding means ineffective. Fig. 5 is a perspective view of the platen roll of a writing machine and 40 associated parts to which has been applied a different embodiment of the positive record material feeding device. Fig. 6 is an end elevation of the construction illustrated in Fig. 5, showing the frictional feeding rollers in operative relation. 45 Fig. 7 is a similar view, showing the feeding devices retracted. Fig. 8 is a similar view, showing the feeding devices reversed and the positively engaging device in operative relation and the frictional rollers retracted. Fig. 9 is a further modification wherein the positive feeding device is mounted for movement into and out of 50 engaging relation with the record material.

55 Like parts are indicated by similar characters of reference throughout the several views.

Referring to the drawings, 1 indicates the rotary platen roller of a conventional typewriter of which 2 is the trunnion shaft carrying the terminal knobs 3 for manual manipulation. The platen roller 1 is normally actuated by the customary line spacing mechanism controlled by the 60

spacer lever 4 shown in Figs. 6 and 7. Associated with the platen roll 1 are frictional rollers 6 and 7 cooperating with the platen roll 1 to progressively advance thereabout and past a writing position indicated by the type bars 5, a plurality of superposed plies of record material 8. The record material 8 is advanced about the platen roll intermediate such platen roll and the frictional pressure rollers 6 and 7 by the rotation thereof. The frictional pressure rollers 6 and 7 are adjustable into and out of cooperative relation with the platen roll 1 to operatively engage and release the record material 8 by means of an oscillatory throw-out lever 10. The particular throw-out and control mechanism for the pressure rollers illustrated in Figs. 2, 3, 6 and 7 is that of a well known and popular type of writing machine, here shown for illustrative purposes only. It is to be understood that the present invention is not dependent upon this specific type of throw-out mechanism, but may be employed with any suitable release means for the frictional feeding device. In the construction adopted for illustrative purpose, the throw-out lever 10, which is pivoted at 11 to a portion of the writing machine platen carriage, is provided with an arcuate cam slot 12 within which engages a roller 13 carried by one arm 14 of a bell crank lever. The other arm 15 of the lever engages with a beak-like projection 16 upon a swinging mounting arm 17 which in turn carries the pressure roller 6. The second pressure roller 7 is carried by a cooperating swinging arm 18, pivoted at 19, and provided with a projecting stud or pin 20 with which one end of the swinging arm 18 has operative engagement. The swinging arms 17 and 18 are normally subjected to spring influence by which they are oscillated to press the rollers 6 and 7 against the periphery of the platen roll 1 or against the record material 8 interposed therebetween. Upon depression of the throw-out lever 10 from the position shown in Fig. 6 to that illustrated in Fig. 7, the bell crank lever is oscillated and by the interengagement of the arm 15 with the beak-like projection 16 the swinging mounting arm 17 is oscillated away from the platen roll 1, carrying with it the pressure roller 6 and, at the same time, through its interengagement with the pin or stud 20 effecting a like outward swinging movement of the second mounting arm 18 to withdraw the second pressure roller 7. The retracted or inoperative relation of the frictional pressure rollers 6 and 7 is illustrated in Fig. 7.

Referring particularly to the embodiment of the invention illustrated in Figs. 1 and 2, there is mounted above the platen roll 1 a frame including a vertical guide plate 21 disposed in a vertical plane substantially tangential with the platen roll 1 and having rearwardly extending ends 22 provided with dependent bifurcated legs 23 which straddle the trunnion shaft 2 of the platen roll to relatively locate the frame structure. The lower margin 24 of the vertical plate 21 is deflected upwardly and rearwardly in spaced relation above the platen roll 1 to afford an alternative guide for the record material 8. Secured to the terminal portions 22 are horizontal brackets or bars 25 to be secured by screws 26 to the reciprocating platen carriage of a writing machine. Revolubly mounted in notches 26a in the top margins of the terminal portions 22 of the frame is a shaft 27 carrying pin wheel units 28 which are longitudinally adjustable upon the shaft 27 to accommodate record material of dif-

ferent widths. The vertical guide plate 21 is provided at spaced intervals with slots 29 through which the radial pins 30 of the pin wheel units project into engagement within the marginally punched holes 31 in the record material 8. The pin wheel units 28 are splined upon the shaft 27 and are held thereon in adjusted relation with their feeding pins projecting through the selected slots 29 by set screws 32. At the front of the guide plate 21 there is disposed a transverse rod 33 supported in brackets or ears 34 upon which are adjustable mounted slotted paper guides 35, between which guides and the plate 21 the marginally punched paper or record material 8 is directed. These slotted guides 35 are adjusted into registry with the slots 29 of the guide plate 21 and serve to retain the punched record material upon the feeding pins 30.

The shaft 27 and pin wheel units 28 are rotated in unison with the platen roll 1 by a train of gear pinions comprising the gears 36 and 37 mounted upon the trunnion shaft 2 and pin wheel shaft 27 respectively and interconnected by an intermediate idler pinion 38.

The pin wheel shaft 27 is removably retained within its bearing slots in the terminal portions 22 of the supporting frame by slide bars 39 secured in position by a clamp screw 40.

In the use of this auxiliary device, the record material 8 is fed over the usual paper guide 41 at the rear of the platen roll 1 and thence circumferentially beneath the platen roll intermediate the frictional pressure rollers 6 and 7 and past the writing position 5. In the event that the record material is to be positively fed past the writing position, the pressure rollers 6 and 7 are retracted to inoperative relation with the platen roll by movement of the throw-out lever 10 and the marginally punched record material is extended upwardly beyond the writing position over the guide plate 21 and beneath the paper guides 35 where it is engaged by the feeding pins 30 of the pin wheel units 28. The pin wheel units 28, being rotated in unison with the platen roll 1 by means of the gear train 36, 37, 38, the record material is positively advanced by the progressive engagement of the pins 30 in the marginal holes 31. In the event that unpunched record material is to be fed or if conditions are such that positive feeding is not necessary, the material may be frictionally fed about the platen roll 1 by manipulating the throw-out lever 10 to return the frictional pressure rollers 6 and 7 into cooperative relation with the record material and platen roll. In such case the inscribed portions of the record material beyond the writing position may be deflected rearwardly over the top of the platen roll 1 and beneath the guide portion 24 of the plate 21. In such path of travel it is not engaged by the positively feeding pin wheel units which operate idly. In lieu of deflecting the inscribed portions of the record material out of the path of operative engagement of the pin wheel units, the pin wheel feeding devices may be bodily removed by releasing the set screw 40 and withdrawing the retaining slide 39, whereupon the shaft 27 and pin wheel unit 28 may be lifted from the slotted bearings in the top of the portions 22 of the supporting frame.

In Fig. 3 there is shown a modification wherein an idler roller 42, mounted upon a swinging bail or frame 43 and resting lightly upon the top of the platen roll 1, serves to guide the inscribed portions of the record material rearwardly over the platen roll and out of the path of operative

engagement of the pin wheel feeding device. The guide roller 42 serves the same purpose as the rearwardly and upwardly extending guide plate 24 on the construction illustrated in Fig. 2.

While it is preferred to render the frictional feeding rolls ineffective during the period of operation of the positive record material feeding means by retracting them away from the platen roll by manipulation of the throw-out lever 10, other means may be provided for effecting the same result without departing from the spirit of the invention. For illustrative purposes, there is shown in Fig. 4 an arcuate paper guide plate 44 underlying the frictional pressure rollers 6 and 7, about which the record material 8 is conducted from the paper guide 41 without passing intermediate the frictional pressure rollers and the platen roll.

In Figs. 5, 6 and 7 there is illustrated an alternative construction wherein in lieu of the pin type feeding device mounted above the platen roll and beyond the writing position, as heretofore described, there are provided pin wheel units 28a carried upon a transverse shaft 27a, mounted in extensions of the swinging arms 18 which carry the frictional pressure roller 7. As illustrated in Figs. 6 and 7, the swinging arms 18 are elongated beyond their pivotal connections 19 for rocking motion in unison with the rocking movement of the arms 17 carrying the pressure rollers 6 which are actuated by the throw-out lever 10. The pin wheel units 28a being connected with the friction rollers 7 for rocking motion about the pivotal stud 19, alternate with the friction pressure rollers in their relation to the record material. That is to say the rocking motion of the swinging arms 18, incident to the adjustment of the pressure rollers 6 and 7 into cooperative relation with the platen roll to frictionally feed the record material thereabout, effects a simultaneous retraction of the positive pin type feeding devices 28a away from operative relation with the record material, and vice versa, the retraction of the frictional pressure rollers to inoperative position effects movements of the pin wheel units 28a into feeding engagement with the marginally punched material. The ends of the platen roll 1 are provided with peripheral grooves affording clearance for the feeding pins of the pin wheel units 28a. If it is desired to write beyond such peripheral grooves, particularly when the positive feeding device is ineffective and the frictional pressure rollers are being relied upon for record material feeding action, a suitable guard or mask 45, supported upon a transverse rod 46, overlies and closes the peripheral groove at the writing line but allows the feeding pins to enter such groove below the end of the shield or mask.

Paper guide fingers 47 are provided in overlying relation with the record material above the platen roll 1 and serve to direct the inscribed portions of the record material rearwardly.

In Fig. 8 there is shown a further variation of the embodiment illustrated in Figs. 2 and 3, wherein the pin wheel shaft 27 and positive feeding members 28 are carried by a swinging arm 48 pivoted upon the trunnion shaft 2 of the platen roll 1 for bodily swinging movement toward and from the path of travel of the record material. In this construction, the end portion 22 of the record material guide plate 21 is formed with an arcuate slot 49, and the swinging arm 48 is provided with a clamp stud 50 engaging in the slot 49 and adapted to hold the arm and the pin wheel units carried thereby in their forward po-

sition wherein the path of the travel of the feeding pins 30 intersects the path of travel of the record material over the plate 21 and beneath the paper guides 35. As illustrated in Fig. 8 the intermediate idler pinion 38 is also carried by the swinging arm 48 whereby the motion transmitting gears 37 and 38 have planetary movement about the gear 37 carried by the platen roll 1. During periods of effective operation of the frictional feeding devices for feeding the record material about the platen roll independently of the pin wheel units, the latter may be retracted to inoperative position shown by dotted lines in Fig. 8 by a swinging movement of the carrying arms 48. During alternating periods of positive advancement of the record material, during inoperative periods of the frictional feeding devices, the arm 48 is adjusted to its forward position wherein the pin wheel units have operative engagement with the record material being advanced over the guide plate 21. Thus, in the construction shown in Fig. 8 the positive feeding device is adjustable relative to the path of movement of the record material, whereas in Figs. 2 and 3 the path of the record material is variable relative to the positive feeding device. Likewise, in the construction illustrated in Figs. 5, 6 and 7, the pin type feeding devices are bodily movable into and out of operative relation with the record material. In the construction shown in the latter figures the adjustment of the throw-out lever 10 to a mid-range position will temporarily maintain both the frictional feeding rollers 6 and 7, and the pin type feeding devices 28a out of engagement with the record material while the latter is being adjusted about the platen roll into proper relation with the writing position and usual line spacing devices.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A writing machine wherein a rotary platen roll and associated frictional feeding devices collectively advance superposed plies of record material to a writing position upon rotation of the platen, characterized by a pin type feeding device mounted in eccentric relation with the platen roll and engageable collectively with all the plies of the record material to positively advance the record material to the writing position alternately with periods of advancement by the frictional feeding means, a swinging carrier for the pin type feeding device by the to and fro motion of which the pin type feeding device is shifted into and out of feeding relation with the record material.

2. A writing machine having a platen and a

writing position past which record material is progressively advanced, characterized by frictional feeding means for feeding superposed plies of record material past the writing position without maintenance of registry, a pin type feeding device for positively feeding the record material past the writing position while maintaining registry of superposed plies thereof, the respective feeding means being operative to advance all of the plies of record material either impositively or positively at equal rates of speed, and guide means for defining alternate paths of travel of the record material relative to the pin type feeding device whereby the record material may be directed at will into or out of interengaging relation with the pin type feeding device.

3. A writing machine wherein a friction feeding device including feed rollers one of which functions as a platen operate to feed record material past a writing position, characterized by a pin feeding device removably mounted in offset relation with respect to said platen and engageable with the record material alternately with the frictional feeding device for advancing the record material at substantially the same rate of speed, said pin feeding device being pivotally mounted for swinging movement into and out of operative position.

4. A writing machine wherein a friction feed device is engageable with record material to advance the material past a writing position, characterized by a pin feeding device also engageable with the record material alternately with the friction feed device and a support for said pin feeding device removably carried by the writing machine, said support including means permitting the movement of the pin feeding device into and out of operative position and actuating means for the respective feeding devices by which the record material is advanced at the same rate of speed by each feeding device.

5. A writing machine including a friction feeding device, and a pin feed device alternately engageable with record material to advance the material past a writing position at substantially equal rates of speed, and a common mounting for the friction and pin feed devices pivotally mounted for oscillation about an axis offset with respect to the said feed devices and adapted to present said devices alternately in operative position by its oscillatory movement.

6. A writing machine wherein superposed plies of record material are progressively advanced past a platen and a writing position by frictional feeding means without regard to registry of superposed plies thereof, characterized by a pin type feeding device eccentrically mounted with respect to the platen for positively feeding the record material past the writing position, while maintaining superposed plies thereof in registry, actuating means for operating the frictional feeding means and the pin type feeding device to advance all the plies of the record material at substantially equal rates of speed by either one such means, and guide means for defining the path of travel of the record material, the path of travel of the record material and the pin type feeding device being variable one relative to the other to effect intermittent operative interengagement thereof.

7. An optionally selective dual feeding means for a writing machine including a rotary platen roll, about which record material is circumferentially advanced past a writing position, frictional feeding means cooperating with the platen to

advance the record material past the writing position, a pin wheel feeding device engageable in marginally punched holes in the record material for positively feeding the record material past the writing position independently of the frictional feeding means, an oscillatory carrier common to the frictional feeding means and to the pin wheel feeding device, and control means for oscillating the carrier to effect alternate feeding engagement of the frictional feeding means and the pin wheel feeding device with the record material.

8. A writing machine having optionally selective dual record material feeding means effective alternately for collectively feeding all of the superposed plies of a manifolding assembly either frictionally or positively past a writing position, each to the exclusion of the other, characterized by a rotary pin type feeding device mounted in eccentric relation beyond the periphery of the platen and engageable in spaced holes in the manifolding material for positively collectively advancing all of the record material plies past the writing position to the exclusion of the frictional feeding means, and selective guide means defining alternative paths of travel through which the record material may be advanced by the respective feeding devices.

9. A writing machine having optionally selective dual record material feeding means effective alternately for collectively feeding all of the superposed plies of a manifolding assembly either frictionally or positively past a writing position, characterized by a rotary pin type feeding device mounted in eccentric relation to and beyond the periphery of the platen roll operable for collectively feeding all of the plies of a manifolding assembly past the writing position independently of the operation of the frictional feeding means, and a deflector for guiding the record material out of feeding relation with the pin type feeding means when the frictional feeding means is in operation.

10. A writing machine having optionally selective dual record material feeding means effective alternately for collectively feeding all of the superposed plies of a manifolding assembly either frictionally or positively past a writing position, characterized by a rotary pin type feeding device mounted in eccentric offset relation to and beyond the periphery of the platen roll for collectively feeding all of the plies of a manifolding assembly past the writing position independently of the operation of the other feeding means, the pin type feeding means and frictional feeding means being mounted one in advance of the other relative to the path of travel of the record material whereby such material idly passes one of the feeding means in its progress to the other feeding means and means associated with the respective feeding means for rendering either of the feeding means ineffective at the will of the operator during the operation of the other.

11. A writing machine having optionally selective dual record material feeding means effective alternately for collectively feeding all of the superposed plies of a manifolding assembly either frictionally or positively past a writing position, each to the exclusion of the other, characterized by a pin type feeding means mounted in eccentrically offset relation to and beyond the periphery of the platen roll each operable independently of the other feeding means for collectively feeding all of the plies of a manifolding assembly past the writing position, and means

for selectively deflecting the record material into the path of travel wherein it is engaged by the pin type feeding means or into a path of travel independently thereof when fed by the frictional feeding means.

12. A writing machine wherein frictional feeding rollers cooperate with a platen roller for frictionally feeding record material past a writing position and having throw out means for rendering the frictional feeding rollers temporarily ineffective, characterized by a pin type feeding device mounted in eccentrically offset relation beyond the periphery of the platen roll for progressive engagement in series punched holes in the material to positively advance the record material past the writing position independently of the operation of the frictional feeding rollers, and control means for rendering the pin type feeding devices ineffective, said friction rollers and pin type feeding device being alternately usable at the will of the operator for feeding the record material.

13. In a writing machine wherein frictional feeding rollers cooperate with a platen roller for collectively feeding multiple superposed strips of record material frictionally past a writing position and having throw out means for rendering the frictional feeding rollers temporarily ineffective characterized by a pin type feeding device mounted in eccentrically offset relation beyond the periphery of the platen roll for progressive engagement in series punched holes in the material to collectively advance the same multiple superposed strips of record material positively past the writing position independently of the operation of the frictional feeding rollers, and guide means for the record material by which the multiple superposed strips of material are collectively guided into position for feeding engagement by the pin type feeding device while the frictional feeding rollers are ineffective, and for collectively deflecting the record material out of position for engagement by said pin type feeding device during periods of operation of the frictional feeding rollers, said frictional rollers and pin type feeding device being alternately usable at the will of the operator for collectively feeding the record material past the writing position.

14. A writing machine wherein frictional feeding rollers cooperate with a platen roll for frictionally advancing record material past a writing position, characterized by a pin type feeding device mounted eccentrically relative to the platen roll beyond the periphery thereof and engageable in spaced holes in the record material for feeding the record material past the writing position alternately with the feeding operation of the frictional rollers, and throw out means associated with the frictional rollers and pin type feeding device for alternating the feeding engagement thereof with the record material.

15. A writing machine wherein frictional feeding rollers cooperate with a platen roll to intermittently advance record material past a writing position, characterized by a pin type feeding device mounted in offset relation beyond the periphery of the platen roll and progressively engageable in spaced holes in the record material for advancing the record material past the writing position alternately with the feeding operation of the frictional rollers and a throw out means for rendering the pin type feeding device ineffective during operative periods of the frictional rollers.

16. In a writing machine, optionally selective

eccentrically offset dual record material feeding means independently effective for feeding superposed manifolding forms either frictionally or positively past a writing position including rotary pin type feeding means having, when selected, positive engagement in spaced holes in the manifolding forms to advance the forms in relative registry past the writing position, the manifolding forms being fed past the writing position without necessarily being in registry when the frictional feeding means is selected and operated to advance the material, the respective feeding means being each operable independently of and to the exclusion of the other to accordingly feed the manifolding forms at the will of the operator.

17. In a writing machine optionally selective dual record material feeding means mounted in relatively offset relation and alternately effective for feeding superposed plies of record material past a writing position including a rotary pin wheel feeding device progressively engageable in series punched holes in the record material for positively advancing the superposed plies thereof in registry past a writing position, and frictional feeding means including a platen roll located in eccentrically offset relation beyond the periphery of the rotary pin wheel feeding device and a throw out lever associated with the frictional feeding means for effecting alternate feeding engagement of the respective feeding means with the record material each to the exclusion of the other.

18. The combination with a writing machine wherein superposed plies of record material are progressively advanced about a rotary platen and past a writing position, of a super-structure mounted upon the writing machine, comprising a frame, a rotary shaft mounted therein, a gear carried by the shaft, an idler gear also mounted in said frame for intermeshing engagement with the gear upon said shaft, a gear rotating in unison with the rotary platen, with which the idler gear simultaneously meshes, a pair of relatively spaced rotary pin wheel units carried by the shaft for unison rotation engageable in relatively spaced holes in the record material from the rear side thereof and axially adjustable to and from each other to accommodate record material of different widths, and recessed record material retaining members overlying the rotary pin units within the recesses of which the feeding pins of said pin wheel units extend through the holes in said record material to prevent displacement of the record material therefrom, said pin wheel units being operable by rotation of the platen for advancing the record material relative thereto.

19. The combination with a writing machine having a platen and a writing position past which record material is progressively advanced, of a pin type feeding device having its feeding engagement with the record material at a point located beyond the writing position for positively advancing the record material past the writing position in a predetermined path of travel, and a movable support therefor upon which the pin type feeding device is mounted for bodily movement toward and from the path of the record material into and out of interengaging relation therewith.

20. The combination with a writing machine having a platen and a writing position past which record material is progressively advanced, of a rotary pin wheel unit for positively feeding the record material past the writing position in a

predetermined path of travel, and an oscillatory carrier for the pin wheel unit upon which the pin wheel unit is mounted for to and fro bodily swinging motion toward and from the path of travel of the record material into and out of interengaging relation therewith.

21. In a front strike typewriting machine, a sheet feeding coupling having, in combination, a revoluble platen having at its ends recesses disposed circumferentially thereabout, a pair of bodily movable wheels having impaling pins engageable in marginal holes formed in the work sheet that is fed between the pin wheels and the platen, the pins on the wheels entering within the recesses in the platen and a control means to carry the pin wheels away from the platen.

22. In a front strike typewriting machine, a sheet feeding couple having, in combination, a revoluble platen having at its ends recesses disposed circumferentially thereabout, a pair of bodily movable wheels having impaling pins engageable in marginal holes formed in the work sheet that is fed between the pin wheels and the platen, the pins on the wheels entering within the recesses in the platen, control means to carry the pin wheels away from the platen and means to latch the wheels away from the platen releasable at the will of the operator.

23. In a front strike typewriting machine, a sheet feeding couple having, in combination, a revoluble platen having at its ends recesses disposed circumferentially thereabout, a pair of bodily movable wheels having impaling pins engageable in marginal holes formed in the work sheet that is fed between the pin wheels and platen, the pins on the wheels entering within the recesses in the platen, control means to carry the pin wheels away from the platen, a releasable set of feed rolls to run upon the bottom of the platen, springs to press said rolls against the platen and a control lever common to the feed rollers and pin wheels for enabling simultaneous adjustment thereof relative to the platen.

24. In a front strike typewriting machine, a sheet feeding couple having, in combination, a revoluble platen having at its ends recesses disposed circumferentially thereabout, a pair of bodily movable wheels having impaling pins engageable in marginal holes formed in the work sheet that is fed between the pin wheels and the platen, the pins on the wheels entering within the recesses in the platen, control means to carry said pin wheels away from the platen, a releasable set of feed rolls to run upon the bottom of the platen, an operative connection between the feed rolls and pin wheels for effecting simultaneous adjustment of the feed rolls and pin wheels relative to the platen.

25. In a front-strike typewriting machine, a sheet-feeding couple having, in combination, a revoluble platen having recesses at its ends, and a pair of wheels having impaling pins to fit in marginal holes formed in the work-sheet that is fed between the pin-wheels and the platen, the pins on the wheels projecting within the recesses in the platen.

26. In a front-strike typewriting machine, a sheet-feeding couple having, in combination, a revoluble platen having recesses at its ends, a pair of wheels having impaling pins to fit in marginal holes formed in the work-sheet that is fed be-

tween the pin-wheels and the platen, the pins on the wheels extending within the recesses in the platen, and a shaft extending along the front of the platen and carrying said pin-wheels.

5 27. In a front-strike typewriting machine, a sheet-feeding couple having, in combination, a revolute platen having recesses at its ends, a pair of wheels having impaling pins to fit in marginal holes formed in the work-sheet that is
10 fed between the pin-wheels and the platen, the pins on the wheels extending within the recesses in the platen, and a control lever having means to carry said pin-wheels away from the platen at will.

15 28. In a front-strike typewriting machine, a sheet-feeding couple having, in combination, a revoluble platen having recesses at its ends, a pair of wheels having impaling pins to fit in marginal holes formed in the work-sheet that is
20 fed between the pin-wheels and the platen, the pins on the wheels extending within the recesses in the platen, and springs to hold the wheels against the paper to press it against the platen.

against the paper to press it against the platen.

29. In a front-strike typewriting machine, a sheet-feeding couple having, in combination, a revoluble platen having recesses at its ends, a pair of wheels having impaling pins to fit in marginal holes formed in the work-sheet that is fed between the pin-wheels and the platen, the pins on the wheels extending within the recesses in the platen, a control lever having means to carry said pin-wheels away from the platen at will, and means to latch said wheels away from the platen.

35 30. In a front-strike typewriting machine, a sheet-feeding couple having, in combination, a revolute platen having recesses at its ends, a pair of wheels having impaling pins to fit in marginal holes formed in the work-sheet that
40 is fed between the pin-wheels and the platen, the pins on the wheels extending within the recesses in the platen, a control lever having means to carry said pin-wheels away from the platen at will, a releasable set of feed-rolls to run upon the bottom of the platen, springs to press said rolls against the platen, and means to enable said control lever to restore said feed-rolls when releasing said pin-wheels from the platen.

releasing said pin-wheels from the platen.

31. A writing machine having a rotary platen roll about which record material is progressively advanced past a writing position, characterized by a guide plate located beyond the platen roll in the direction of travel of the record material, having therein a slot, a series of traveling feeding pins operative in a path of travel coincident with said slot and engageable in relatively spaced holes in the record material for advancing the material relative to the guide plate and past the writing position, and a carrier for the pins causing the pins to describe arcuate movements in reverse directions contiguous to the ends of the slot by which the pins are projected through a swinging motion from beyond said guide plate through the slots thereof into engagement with corresponding holes in the record material and are subsequently withdrawn therefrom through the slot by a swinging motion by which the record material is stripped from the pins preparatory to the return thereof to the material engaging end of the slot.

JOHN Q. SHERMAN.
